UNITED STATES PATENT OFFICE

MICHAEL SCHWARTZ, OF CHICAGO, ILLINOIS, ASSIGNOR, BY MESNE ASSIGNMENTS, TO
AUTOMATIC ELECTRIC INC., OF CHICAGO, ILLINOIS, A CORPORATION OF DELAWARE

TRAFFIC RECORDER FOR TELEPHONE SYSTEMS

Original application filed July 12, 1922, Serial No. 574,494. Patent No. 1,668,541, dated May 1, 1928.
Divided and this application filed April 2, 1925. Serial No. 20,044.

The present invention relates in general to traffic recorders for telephone systems. More specifically, the invention is concerned with devices which record the traffic on trunks extending between automatic switches.

An object of the invention is to provide a recording device for registering the number of times a trunk line is seized and then released within a very short interval, together with means for registering the number of times the trunk line is used for a longer interval as for a successful call to a called line.

Another object of the invention is to provide a device for registering the total length of time the trunk line is in use.

Another object of the invention is to register the number of times all the trunks in a group become busy, and also to record the total length of time that this all trunk busy period lasts.

Still another object of the invention is to provide means for at all times showing the number of simultaneous connections over this group of trunks under observation.

A further object of the invention is to provide an improved timing device, whereby the recording mechanism may be controlled at various speeds.

The various features above mentioned, except those relating to the timing device are claimed in my application Serial No. 574,494, filed July 12, 1922, patented May 1, 1928, Patent No. 1,668,541, of which this application is a division.

Referring now to the drawings, comprising Figs. 1 and 2, there is shown sufficient apparatus involving the invention to enable the same to be readily described and understood. Fig. 1 shows the traffic recording apparatus, while Fig. 2 shows the improved timing device.

Referring now more particularly to Fig. 1, in the upper portion of the drawing, designated by the reference character E, is an automatic selector switch of the usual Strowger type, the construction and circuits of which are well understood.

At A is indicated a recording milli-ammeter for registering the total number of simul-

taneous calls in the group of trunks under observation. This milli-ammeter may be of any well-known or desired type.

The traffic recording device proper consists of the equipment designated by the reference characters M and M'. The equipment shown at M consists merely of a group of meters 100, 101, and 102, which record the required data. The equipment shown at M' consists of two meters 88 and 89, a group of relays, and a simple rotary minor switch S'. This equipment controls the operation of the meters 100, 101, 102 and also the meters 88 and 89.

The equipment shown at M may be used alone without the equipment M', if it is desired to merely register the total number of calls over a trunk line, and the total length of time the trunk is held in use. In the present instance, it will be assumed that it is desired to record the traffic on a group of ten trunks. In this case, each trunk line will have individual to it apparatus such as M and M'. Thus, the equipment M and M' is individual to the trunk line comprising conductors 10-12, inclusive, with the exception of the meters 89 and 102. The meter 89 is common to the ten trunk lines of the group and serves to register when all trunks become busy. The meter 102 is likewise common to the ten trunk lines and registers cumulatively the total length of time all ten trunks are in use.

The recording apparatus including the equipment M and M' may be used to record the traffic on a trunk line extending from a line switch to a first selector, a selector trunk line, or in fact, any kind of trunk over which it is desired to record the traffic.

In Fig. 2, there is shown the timing mechanism. This is common to all the traffic recording devices of the exchange, and comprises essentially a constantly operating timing device P and two rotary switches C and S. The rotary switch S is of very simple construction and comprises wipers 180 and 181, an operating magnet 168 and a release magnet 169. The rotary switch C, whose wipers move in a forward direction only, is

100

of the same general mechanical construction as the well-known rotary line switches.

Having briefly described the apparatus shown in the drawings, a detailed description 5 of its operation will now be given. For this purpose it will be assumed that the trunk line comprising the conductors 10-12 inclusive, is seized by another selector switch or by a line switch under the control of a 10 calling subscriber. Immediately upon the subscriber's line being extended to the line relay 15 of the selector E, this relay is energized. Upon operating, relay 15, at armature 20, closes the circuit of the slow acting 15 relay 16. The latter relay, upon energizing, at armature 21 prepares the operating circuits of the selector E, and at armature 22 places ground upon the release trunk conductor 11, thereby establishing a holding circuit 20 for the preceding switch or switches.

The calling subscriber may now operate his calling device in accordance with the next digit in the desired number. By this operation a series of interruptions is produced in 25 the circuit of the line relay 15 of the selector E, which deenergizes a plurality of times in response thereto. At each retraction of the armature 20 of the line relay 15, an impulse of current is sent to the vertical magnet 46 30 in series with the slow acting relay 17. The vertical magnet 46 operates to raise the shaft of the switch carrying the wipers 35-37, inclusive, step by step until the said wipers are brought opposite the proper level of bank 35 contacts. The slow acting relay 17 is energized in series with the vertical magnet, and maintains its armature attracted throughout the vertical movement of the switch. Upon the first vertical step of the switch shaft, the 40 relay 17 being now energized, a circuit is completed for the stepping relay 18. Upon operating, relay 18 establishes a locking circuit for itself at its upper armature, and at its lower armature prepares a circuit for the 45 rotary magnet 44. Shortly after the end of the vertical movement, the slow acting relay 17 deenergizes to close the circuit of the rotary magnet 44. The magnet 44 operates to advance the switch wipers into engagement 50 with the first set of bank contacts in the selected level, and also opens the locking circuit of the stepping relay which deenergizes, opening the circuit of the rotary magnet which deenergizes also. If the trunk line 55 with which the switch wipers are now in engagement is busy, the stepping relay 18 will again be energized from ground upon the test contact of the associated trunk line. Relay 18, upon operating, completes a locking 60 circuit for itself and also closes the rotary magnet circuit. The rotary magnet operates to advance the wipers of the switch into engagement with the next set of bank contacts and opens the circuit of the stepping relay. 65 The stepping relay deenergizes to open the

circuit of the rotary magnet, which also de-energizes. The alternate operation of the relay 18 and the rotary magnet 44 continues until the wipers of the selector E are rotated into engagement with a set of bank contacts 70 associated with an idle trunk line, which, we will assume, are the bank contacts 38-40, inclusive. When the wipers 35-37, inclusive, are brought into engagement with this set of bank contacts, the rotary movement of the selector E ceases, and the switching relay 19, 75 which during the preceding operations of the switch has been short circuited, is energized in series with the stepping relay 18. Relay 19 operates to extend the calling line over the 80 wipers 35 and 37, bank contacts 38 and 40, trunk conductors 41 and 43, to the windings of the line relay of the seized switch.

The line relay of the selected switch immediately energizes to close the circuit of its 85 associated slow acting release relay. The latter relay operates to prepare the circuits of the seized switch for operation, and to place ground upon the release trunk 42 to establish a holding circuit for the selector E 90 and the preceding switch or switches.

The further extension of the connection in response to the remaining digits dialled by the calling subscriber will take place in the usual manner, and as this extension does not 95 concern the present invention, it will not be described herein.

It will be noted that as soon as the selector E is seized, ground is placed upon the release trunk conductor 11, and a circuit is completed extending from this ground over conductor 13, terminal 50 of the recording device M, through the resistance 60, and through the recording milli-ammeter A to battery. The current flowing through the resistance 60 and 100 the winding of the milli-ammeter affects the marking pen in the usual manner, causing the line of the chart to be raised a suitable distance to indicate another call. All the release trunks of the group of trunks are 105 connected through a resistance similar to 60 to the recording milli-ammeter, so that the reading of the milli-ammeter is always proportionate to the number of simultaneous calls in the group. The resistances, such as 110 60, are sufficiently high so that there is no interference by a ground potential being extended through these resistances to the other release conductors of the trunks of the group when one or more become busy. There is 115 also another circuit completed by the grounding of conductor 11, which extends from terminal 50 by way of terminal 51, working contact of spring 62 of key K and the said spring, this key being in operated position when it 120 is desired to record the traffic on the associated trunk, terminal 52, terminal 55, through the winding of the high resistance relay 70, through the winding of the low resistance relay 71, terminals 56 and 53, and through the 125 130

windings of the meter magnet 100 to battery. Only the high resistance relay 70 is operated over the above circuit. Upon attracting its armatures, relay 70, at armature 76, closes a circuit which extends from ground by way of the front contact of armature 76 and the said armature, terminals 57 and 54, working contact of spring 61 and the said spring, through the winding of the meter magnet 101, conductor 112, to terminal 163 of the timing device. The terminal 163 of the timing device is being connected to battery once every second by the operation of the timing mechanism, as will be described, and consequently, the meter magnet 101 is operated to register every second, thus indicating by its cumulative registration for various calls the total length of time that the trunk is held in use. Further results of the energization of relay 70 are that at armature 77 a circuit is prepared for the release magnet 74 of the minor switch S', at armature 78 a point is closed in a certain chain circuit, which will be described, and at armature 79 the rotary magnet 73 of the rotary switch S' is connected over conductor 110 to the terminal 164 of the timing device. The terminal 164 of the timing device is being momentarily connected to battery once every half second, as will appear later, and consequently motor magnet 73 operates to advance the wiper 95 one step every half second. At the end of four seconds, the wiper 95 is advanced into engagement with the bank contact 96, whereupon the winding of the relay 70 is short circuited. By this operation relay 71 and the meter magnet 100 are energized. Upon operating, relay 71, at armature 80, establishes a locking circuit for itself exclusive of the wiper 95, at armature 81 closes a new circuit for the meter 101, at this same armature closes the circuit of the slow acting relay 93, at armature 82 closes a circuit for the release magnet 74 of the minor switch S', at armature 84 closes a new point in the chain relay above mentioned to provide against the deenergization of relay 70, and at armature 85 transfers the circuit of the motor magnet 73 of the minor switch S' from connection with the terminal 164, into connection with the terminal 165 of the timing device. As the winding of relay 70 has been short circuited by the operation of wiper 95 of the switch S', this relay will deenergize. However, due to the fact that it is short circuited, it will be made slow acting and maintain its armature attracted for a short interval after the short circuiting of its winding, long enough to allow the minor switch S' to be released. The operation of the meter 100 serves to register one call. The slow acting relay 93, upon operating, at armature 87 opens a point in the circuit of relay 72, and at the front contact of this armature prepares a circuit for the release magnet 74. As the motor magnet

73 of the minor switch S' is now connected to the terminal 165 of the timing device, it will be operated once every 50 seconds. Each time the magnet 73 operates it advances the wiper 95 one step. At the end of 500 seconds, the wiper 95 will engage the bank contact 97, whereupon, if the connection is not terminated, the lamp L will be lit. The operation of the lamp L serves to notify the attendant at the exchange that the particular trunk having the equipment M has been in use for a prolonged period of time. The attendant may now examine this trunk to see if it is held due to some unnatural condition.

It will be remembered that the relay 71, upon operating closes a point in a certain chain circuit. This circuit includes contacts on other relays, such as relays 70 and 71, in other equipment such as M' which are associated with the other trunks of the group. When all the trunks of the group become busy, the chain is closed, and the meter magnet 89 will be operated to indicate this fact.

It will be noted that each time the timing meter magnet 101 operates, the armature 106 is caused to engage its working contact. This armature and contact is included in another chain circuit which has contacts on various other magnets, such as 101 in the groups of ten trunks with which these meters are associated. When all the trunks of this group of ten become busy, the meter magnet 102 will be operated to denote by its cumulative operation the time that these trunks are held in use.

Should it happen that, when the trunk line comprising conductors 10-12, inclusive, is first seized, the subscriber should replace his receiver before the wiper 95 advanced into engagement with the bank contact 96, the meter magnet 100 would not be operated. However, when the connection is released, the relay 70 will be deenergized, while the minor switch S' will be off normal. The slow acting relay 72 is accordingly energized in series with the release magnet 74, and operates at its armature 86 to close the circuit of the meter 88. Meter 88 operates once to register that the trunk line has only been used for a short period of time, less than four seconds, while magnet 74 operates to restore the minor switch S' to normal.

When the connection is released, ground is removed from the test contact 39 with which the test wiper 36 of the selector E is in engagement, and the selector E is released in the usual manner. When ground is removed from the release trunk conductor 11, the relay 71 in the metering equipment M' is deenergized. By the deenergization of relay 71, the circuit of the slow acting relay 93 is opened. After the deenergization of relay 71 and before the deenergization of relay 93, a circuit is completed for the release mag-

net 74 over the path extending from ground by way of front contact and armature 87, armature 83 and its back contact, back contact and armature 77, off normal spring 75 5 and its working contact, and through the winding of the release magnet 74 to battery. Accordingly, the minor switch S' is released. Another result of the deenergization of relay 71 is that the circuit of the timing meter 10 101 is opened at armature 81. The operation of the other contacts on the relay 71 serve merely to restore certain circuits to normal.

Having described the operation of the metering device when the equipment M' is 15 used, its operation when only the equipment M is used will now be described. In this case, all the terminals 50-54, inclusive, will be connected together. Now, when ground is placed upon the release trunk conductor 20 11 at the time the trunk is seized, the meter magnet 100 is immediately operated to register one connection, and the timing meter 101 immediately starts to operate. The current flowing through the resistance 60, of 25 course, causes the milli-ammeter A to register another connection. When the connection is released the selector E is restored to normal and the equipment M ceases functioning.

30 The operation of the timing device shown in Fig. 2 will now be described. The device P consists of a constantly operating pendulum 150, which is controlled by the relay 151. Its operation is as follows: When the pendulum 35 swings to the left, it closes the springs 150 and 156, whereupon a circuit is completed for the relay 151. Upon energizing, relay 151 attracts its armature 155, as the tension is taken off spring 156, this spring operates and 40 causes the pendulum spring 150 to be forced to the left, thereby moving the pendulum to the right. When the pendulum swings to the right, it opens the circuit of the relay 151, which deenergizes, causing the spring 156 to assume its normal position. The same operation is then repeated. An additional result 45 of the energization of the relay 151 is that at armature 152 battery is connected to the conductor 157, which extends through the stepping magnet 167 of the rotary switch C to ground. The weight on the pendulum 150 is so adjusted that the relay 151 is energized once every half second. The terminal 164 of the timing device thus has battery placed 50 upon it once every half second. The stepping magnet 167 is operated once every half second and serves to advance the switch wipers 175-178, inclusive, one step every half second. In the contact banks adapted to be engaged 55 by wipers 175 and 176, the contacts are tied together alternately. In the bank adapted to be engaged by wiper 175, the first, third, and other odd contacts are connected together and to the terminal 163. In the contact bank adapted to be engaged by wiper

176, the second, fourth, and other even contacts are connected to the terminal 163. The wipers 175 and 176 are set opposite each other so that when the wiper 175 engages the first bank contact, the wiper 176 leaves the twenty-fifth bank contact. By this arrangement the conductor leading to the terminal 163 is connected to battery once every two steps of the wipers 175 and 176. In the contact bank adapted to be engaged by wiper 177, every 70 75 fifth contact is connected together and thence to the terminal 162. Thus, the terminal 162 is connected to battery once every two and one half seconds. Only one contact in the bank adapted to be engaged by wiper 178 is 80 connected to the terminal 160. Another contact is connected to the terminal 161. Thus, the terminals 160 and 161 are connected to battery once every twenty-five seconds, that is, each fifty steps of the wiper 178. The 85 space between the battery impulses at the terminals 160 and 161 is determined by the space between the bank contacts to which these terminals are connected in the bank adapted to be engaged by wiper 178. In 90 95 addition, the wiper 178 in engaging its twenty-fifth bank contact, closes the circuit of the stepping magnet 168 of the minor switch S. Magnet 168 operates to advance the wipers 180 and 181 one step every twenty-five seconds. As alternate contacts in the bank of wiper 180 are connected together and to the terminal 165, this terminal is connected to battery once every fifty seconds. When the wipers 180 and 181 reach their tenth position, the next time the wiper 178 engages its twentieth bank contact, the slow acting relay 170 is energized. Relay 170 operates to close the circuit of the release magnet 169. Magnet 169 operates to restore the minor 100 105 switch S to normal, whereupon the same operation is repeated. In this manner battery is connected to the terminal 164 every one-half second, to the terminal 163 every second, to the terminal 162 every two and one-half 110 115 seconds, to the terminals 160 and 161 every twenty-five seconds, and to the terminal 165 every fifty seconds, whereby the traffic recording devices are controlled as has been described. Terminals 160, 161 and 162 are provided to make it possible to change the rate of operation of time controlled mechanisms of the recording equipment. These terminals may also be utilized in operating other apparatus at the exchange requiring a 120 different rate of operation than could be obtained by connecting with any of the terminals 163, 164, or 165.

What is claimed is:

1. In combination, an impulse conductor, a 125 battery, a rotary switch having a plurality of wipers connected to said conductor, a set of bank contacts accessible to each wiper, means for connecting said conductor to said battery periodically, a plurality of terminals, 130

means controlled over said impulse conductor for operating said switch, and circuit connections between said bank contacts and terminals whereby each of said terminals is 5 connected to battery at different periodic intervals.

2. In combination, an impulsing conductor, automatic means for sending timed impulses over said conductor, a rotary switch 10 having a plurality of wipers and sets of bank contacts, a plurality of terminals wired to different contacts of said sets, and means controlled by said impulses for operating said switch to connect said conductor with 15 each of said terminals at different periodic intervals.

3. In combination, an impulsing conductor, automatic means for sending periodic timed impulses over said conductor, a rotary 20 switch having a plurality of wipers and sets of bank contacts, a plurality of terminals one of which is connected direct to said conductor while the others are each connected to different contacts of said sets, and means controlled over said conductor for operating 25 said switch to connect said conductor with each of said other terminals at different periodic intervals.

4. In combination, an impulsing conductor, automatic means for sending periodic timed impulses over said conductor, a rotary 30 switch having a plurality of wipers and sets of bank contacts, a plurality of timing conductors one of which is directly connected to said impulse conductor while the others are 35 connected to said bank contacts, and means controlled by said impulses for operating said switch to connect said impulse conductor with said timing conductors at periodic intervals 40 different from the intervals on said impulse conductor and different from each other.

5. In combination, a battery, an impulsing conductor, a plurality of terminals one of which is directly connected to said conductor, a 45 rotary switch with a plurality of wipers and corresponding sets of bank contacts, different contacts of the said sets being wired to the other of said terminals, respectively, means for periodically connecting said battery to said conductor, and means controlled 50 over said conductor for operating said switch for connecting said conductor to each of the other of said terminals at different periodic intervals.

55 6. In combination, a conductor, means for connecting a source of current to said conductor periodically, a step by step switch controlled over said conductor, two terminals, a wiper on said switch connected to said conductor, bank contacts associated with said wiper, multiple connections from certain of said bank contacts to one of said terminals, another wiper and associated bank contacts, said other wiper being also connected 60 to said conductor, and multiple connections 65 to said conductor, and multiple connections

from non-corresponding contacts of the second series of bank contacts to the other of said terminals.

7. In combination, a conductor, means for connecting a source of current to said conductor periodically, a step by step switch controlled over said conductor, a second switch controlled by said first switch, two terminals, a circuit including a wiper of the first switch only for connecting said conductor with one of said terminals, and a second circuit including wipers of both switches for connecting said conductor with the other of said terminals. 70 75

8. In combination, a conductor, means for connecting a source of current to said conductor periodically, a step-by-step switch controlled over said conductor, a second switch controlled by said first switch, two terminals, a circuit including a wiper of the first switch only for connecting said conductor with one of said terminals at intervals, and a second circuit including the wipers of both switches for connecting said conductor with the other of said terminals 80 85 90 at longer intervals.

9. In combination, a primary impulse conductor, automatic means for sending periodic timed impulses over said conductor, a rotary switch having a plurality of wipers and sets of bank contacts, a plurality of secondary impulse conductors, one of said secondary conductors being connected to said impulse conductor and said wipers, means controlled over said primary impulse conductor for operating said switch, and connections between the other of said secondary impulse conductors and said bank contacts whereby the second of said secondary impulse conductors receives periodic timed impulses which have twice the interval of time between impulses as said first secondary impulse conductor and the remaining of said secondary impulse conductors receive periodic timed impulses which vary in accordance with the number of multiple connections in said sets of bank contacts. 100 105 110

10. In combination, a conductor, an impulse transmitting device for connecting a source of current to said conductor periodically, a step-by-step switch controlled over said conductor, a wiper on said switch connected to said conductor, bank contacts associated with said wiper, and two terminals, one of said terminals being connected with said conductor and the other of said terminals being connected to certain of said bank contacts, whereby said other terminal is connected to said conductor at certain intervals during the operation of said switch. 115 120 125

11. The combination, with a source of pulsating current of a particular frequency, of a device for producing impulses of a different frequency, said device comprising an automatic switch, a stepping magnet for said 130

switch connected to the source of pulsating current, a wiper for said switch also connected to said source of pulsating current, bank contacts engaged by said wiper, and a conductor over which the pulses of said different frequency are to be delivered which is connected to a plurality of said bank contacts, the number of bank contacts to which said conductor is connected depending on the frequency desired.

- 10 12. In an impulse generating device, a conductor, means for periodically connecting a source of current to said conductor, a step-by-step switch controlled over said conductor, two wipers for the switch each connected to said conductor, sets of bank contacts accessible to said wipers, a terminal, multiple connections from alternate contacts of the first bank to said terminal, and multiple connections from non-corresponding alternate contacts of the second bank to said terminal.
- 15 13. In an impulse generating device, a conductor, means for periodically connecting a source of current to said conductor, a step-by-step switch controlled over said conductor, four wipers for the switch, four sets of bank contacts accessible to said wipers, terminals, multiple connections from odd contacts of the first bank to the first terminal, multiple connections from the even contacts of the second bank to said first terminal, multiple connections from every fifth contact of the third bank to the second terminal, and
- 20 25 30 35

multiple connections from a single contact of the fourth bank to the third terminal.

In witness whereof, I hereunto subscribe my name this 31st day of March, 1925.

MICHAEL SCHWARTZ.
